ARTHUR ERNEST JERRAM, JOSEPH GOULDBOURN, AND ARTHUR BATES, OF LEICESTER, ENGLAND, ASSIGNEES TO UNITED SHOE MACHINERY COMPANY, OF PATERSON, NEW JERSEY, A CORPORATION OF NEW JERSEY.

SHOE-SUPPORT.

1,175,955.

Specification of Letters Patent. Patented Mar. 21, 1916.

Original application filed September 9, 1910, Serial No. 581,171. Divided and this application filed February 19, 1915. Serial No. 9,393.

To all whom it may concern:

Be it known that we, ARTHUR E. JERRAM, JOSEPH GOULDBOURN, and ARTHUR BATES, subjects of the King of England, residing 5 at Leicester, Leicestershire, England, have invented certain Improvements in Shoe-Supports, of which the following description, in connection with the accompanying drawings, is a specification, like reference characters 10 on the drawings indicating like parts in the several figures.

The present invention relates to shoe supporting means for maintaining a shoe in place while it is being operated upon by 15 tools of any description.

The invention is herein shown as embodied in the heelng machine of our application Serial No. 581,171 filed September 9, 1910 of which the present application is a division. In that machine the heel of the shoe is operated upon by drivers or awls but the invention is not limited in its application to this or to any particular type of machine.

In the usual course of shoe manufacturing 25 there are presented to most shoe making machines shoes of various sizes, widths and styles and also right and left shoes of these different shapes. It is important that each shoe, regardless of its shape, should be firmly held in place during the operation of the machine.

It is accordingly an object of the present invention to provide shoe clamping means capable of a wide range of adjustment but 35 constructed and arranged, when the necessary adjustments have been made, to hold each shoe without the liability of displacement.

The features of the invention will be best 40 understood and appreciated from the following description of a preferred embodiment thereof selected for purposes of illustration and shown in the accompanying drawings, in which,—

45 Figure 1 is a plan view of the band clamp and its mounting, and Fig. 2 is a view in side elevation, partly in section, showing the clamping mechanism embodied in a heelng machine.

50 In Fig. 2 the present invention is shown

as embodied in a heelng machine of the character disclosed in our co-pending application above identified. This machine has a frame 16 in which is mounted a plunger 8 carrying the jack 162 and also a plunger 6 55 carrying a gang of tools or drivers 10. The plunger 8 carries also a bracket 164 which carries the shoe clamping elements. It will be understood that the shoe is placed on the jack 162 when the jack is swung outwardly. 60 The jack is thereupon swung rearwardly, carrying the counter portion of the shoe into the band clamp 132 which acts to hold the shoe firmly in place during the subsequent operation of the machine. The bracket 164 65 and the elements carried thereby move up and down with the jack and shoe so that the relationship of these parts when once established is not disturbed until the finished shoe is taken off the jack. In the lower end 70 of the bracket 164 is formed a vertical cylindrical socket for the reception of the shank 154 of the support 150. The end of the bracket 164 is split and there is provided a clamping bolt 155 by which the shank 154 75 may be clamped rigidly in place but which affords provision for a bodily angular adjustment of the support 150.

The support 150 has guideways on its lower face in which is received a sliding section 140. On the upper surface of this section is formed a rack 151 which meshes with a pinion 152 on a cross shaft journaled in the support 150. At its outer end this shaft is provided with a hand nut 153 by which 80 the pinion 152 may be turned and the section 140 moved forwardly or rearwardly in the direction of the longitudinal axis of a shoe on the jack 162. The shaft of the hand nut 153 and the pinion 152 is bored to receive 85 a stationary pin to the outer end of which is secured an eccentric clamping piece 157. When this is swung downwardly a shoulder on the hand nut 153 is forced against a stationary boss on the support 150, thereby 90 locking the section 140 against movement.

At the forward side of the section 140 is formed a yoke 141 forked at its outer ends to receive the levers 134 which are pivoted to the yoke by vertical pins 138. 100

Pivoted to the forward end of each lever 134 is a sleeve 133 and in each of the sleeves is slidably received a rod 144 pivoted at its inner end to an ear on the band clamp 132. 5 Into the outer end of each sleeve 133 is threaded an adjusting screw 142 which bears upon the outer end of the rod 144 and by which each rod may be forced inwardly. The band clamp 132 is of flexible material 10 and has a constant tendency to expand and therefore forces the rods 144 into the sleeves against the ends of the screws 142. It will be apparent that the screws 142 afford convenient means for independently adjusting 15 the sides of the band clamp.

Each of the levers 134 at its inner end carries a threaded stud through which passes an adjusting screw 147 having a right and left thread and a knurled nut 148 at its 20 outer end. By turning this screw the forward ends of the carrying levers 134 may be swung toward or from each other in a symmetrical manner and a corresponding adjustment of the band clamp effected.

25 At the rear of the center of the band clamp 132 there is formed a boss from which projects a threaded rod 166. This rod passes through a bore in the yoke 141 which is cut away to receive an adjusting nut 168. 30 By turning the nut 168 the rod 166 may be moved forwardly or rearwardly and the position of the rear portion of the band clamp thus accordingly adjusted.

From the foregoing description it will be 35 seen that the band clamp has provision for the independent adjustment of its sides and the backward and forward adjustment of its rear portion in addition to provision for a symmetrical, widthwise adjustment of its 40 side portions. By reason of the various adjustments the contour of the band clamp may be made to fit a shoe of any shape or style. Having made these adjustments for a shoe of one size of such style, shoes of different sizes and widths of the same style 45 may be accommodated by merely turning nut 148 on the adjusting screw 147. In addition to these adjustments which affect the band clamp directly there is provision for the backward and forward adjustment of the band clamp bodily without affecting the 50 contour thereof and also a bodily angular adjustment of the entire mechanism. This great flexibility of adjustment adapts the 55 supporting mechanism to receive shoes varying in shape through a very wide range but when the proper adjustments have been made all of such shoes are firmly positioned upon the jack during the operation of the 60 machine.

Having thus described our invention, what we claim as new and desire to secure by Letters Patent is:

1. In a device of the class described, the

combination with a flexible clamping band, 65 of a carrying lever mounted at each side of the band, an adjustable connection between each side of the band and the corresponding lever whereby a non-symmetrical adjustment of the band may be effected, and 70 means for moving both levers equally in opposite directions whereby the size of the band opening may be adjusted while maintaining the non-symmetrical shape of the band. 75

2. In a device of the class described, the combination with a support, of a pair of levers pivoted thereto, a clamping band suspended between the levers and arranged to be symmetrically adjusted by the movement 80 of the levers, and connections having provision for independent adjustment of each side of the band with respect to its associated lever.

3. In a device of the class described, the 85 combination with a support, of a pair of levers pivoted thereto and connected at their rear ends by an adjusting screw, a clamping band carried at the forward end of the levers, and means for independently adjusting 90 the relative positions of each side of the band and its carrying lever.

4. In a device of the class described, the combination with a flexible U-shaped clamping band, a supporting yoke for the band, 95 and connections between the band and yoke including a rod secured to the band at its curved end, said rod being adjustable relatively to the yoke in a direction lengthwise of the band to position the rear portion of 100 the band.

5. In a device of the class described, the combination with a flexible U-shaped clamping band, a supporting member for the band movable bodily lengthwise of the band, and 105 means movable relatively to the supporting member for adjusting the rear portion of the band in the same direction.

6. In a device of the class described, the combination with a flexible clamping band, 110 of carrier members for the band adjustable widthwise of the band, a support for the carrier members adjustable lengthwise of the band, rack and pinion mechanism including a hand nut for effecting the latter 115 adjustment, and locking means disposed axially with respect to the hand nut.

7. In a device of the class described, the combination with a flexible band, of a support having carrier members for the band 120 adjustable widthwise of the band, and also a carrier member connected to the center of the band and adjustable in a direction lengthwise thereof relatively to the support, and means for shifting the support bodily 125 with all of said carrier members in a direction lengthwise of the band.

8. In a heelng machine having a movable

jack, a bracket extending above and behind the jack and having a socket at its lower end, a support adjustably mounted in said socket and including a section adjustable lengthwise of a shoe on the jack, carrier members pivoted to said adjustable section, and a clamping band suspended between said carrier members.

In testimony whereof we have signed our

names to this specification in the presence 10 of two subscribing witnesses.
